(57) **CLAIM**

The ornamental design for a watch component, as shown and described.

DESCRIPTION

FIG. 1 is a front perspective view of a watch component of the present invention;

FIG. 2 is a front elevational view of the watch component of FIG. 1;

FIG. 3 is a rear elevational view of the watch component of FIG. 1;

FIG. 4 is a right side elevational view of the watch component of FIG. 1;

FIG. 5 is a left side elevational view of the watch component of FIG. 1;

FIG. 6 is a top plan view of the watch component of FIG. 1; and,

FIG. 7 is a bottom plan view of the watch component of FIG. 1.

The broken lines shown in the drawings represent portions of a watch which form no part of the claimed design.

1 Claim, 4 Drawing Sheets
